(57) **CLAIM**

The ornamental design for a candle holder with spike, as shown and described.

DESCRIPTION

FIG. 1 is a front, top and left perspective view of the candle holder with spike showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

In the drawings, the broken lines depict unclaimed subject matter only and form no part of the claimed design.
